UNITED STATES PATENT OFFICE.

HERBERT H. BROWN, OF LYNN, MASSACHUSETTS.

UMBRELLA.

No. 852,493.

Specification of Letters Patent.

Patented May 7, 1907.

Application filed November 8, 1905. Serial No. 286,324.

To all whom it may concern:

Be it known that I, HERBERT H. BROWN, a citizen of the United States, residing at Lynn, county of Essex, and State of Massachusetts, have invented an Improvement in Umbrellas, of which the following description, in connection with the accompanying drawings, is a specification, like letters on the drawings representing like parts.

10 This invention relates to umbrellas and particularly to that class of umbrellas which can be taken down or folded into a compact package.

15 The object of the invention is to provide an umbrella of this class which is comparatively inexpensive to manufacture, which can be very readily folded or taken down, which when taken down or folded occupies a small space and can be readily packed in a grip or 20 suit case, and which when opened is as rigid and strong as an ordinary umbrella.

The ribs of my improved umbrella are jointed intermediate of their ends, and the joint is so constructed that in order to fold 25 the umbrella, the jointed ends of the ribs are folded inwardly, and the main portions of the ribs are then folded back against the tip of the umbrella. In order to hold the ribs stiff when the umbrella is open, I have hinged the 30 outer ends of the braces of the ribs to shoes which are adapted to span the joints of the ribs, and thus hold the ribs rigid. The shoes can be readily moved longitudinally of the ribs to allow the joints to fold, and after this 35 is done, the umbrella is folded by merely sliding the runner up on the handle sufficiently far to cause the main portion of the ribs to fold backwardly against themselves and against the tip of the umbrella, the outer 40 or pivoted ends of the ribs during this operation folding inwardly against the main portion of the ribs by the action of gravity. The handle is preferably made detachable from the umbrella frame and may be made in two 45 or more sections, so that it can be detached from the umbrella and taken apart.

I will now describe one embodiment of my invention and then point out the novel features of the invention in the appended 50 claims.

Figure 1 is a view showing an umbrella frame embodying my invention, said frame being shown open; Fig. 2 shows the umbrella frame shown in Fig. 1 partly folded, and in

dotted lines shows said umbrella frame completely folded; Fig. 3 is an enlarged detail of the hinged joint of each rib and the shoe to which the brace is secured; Fig. 4 is a cross section on the line $x-x$, Fig. 3, and Fig. 5 is a view similar to Fig. 3 showing the rib 55 partly folded.

3 designates the head or tip of the umbrella, 4 the handle, 5 the ribs, 6 the runner on the handle, and 7 the braces connecting the runner and the ribs. The ribs 5 are piv- 65 oted at 8 to the head or tip 3 in any suitable way. Each rib is jointed intermediate of its ends at 9, the joint preferably being an inside joint so constructed that the outer end 10 of the rib can fold inwardly against the inside 70 of the upper part 5 of each rib. The ribs are shown as U-shape in cross section, although this particular shape is not essential to the invention.

The main portion 5 of each rib is provided 75 with ears 11 which are hinged to other ears 12 on the outer end 10 of the rib by means of a hinge pin 13. This makes a knuckle-joint which permits the outer end 10 of the rib to fold inwardly, as shown in Fig. 2, but prevents it from folding outwardly. Each brace 80 7 is pivoted at its outer end to a shoe 14 which in this embodiment of my invention is arranged to be received within the U-shaped rib and to slide back and forth across the 85 joint 9. The main portion of the rib is made tubular adjacent the hinge, as at 16, and is also made tubular at a slight distance from the end, as at 15. The inner end of the hinged portion 10 of each rib is also made 90 tubular adjacent the hinge, as at 17. When the umbrella is opened, the shoe 14 occupies the full line position Fig. 3, that is, the end 18 thereof extends into the tubular portion 17 of the hinged end 10 of the rib, and said end also extends through the tubular portion 16 and into the tubular portion 15 of the main body of the rib. When in this position, the shoe spans the joint 9 and holds the rib stiff 95 and straight. If the shoe is moved upwardly on the rib so that the end 18 is clear from the tubular portion 17, then the rib can fold, as shown in Figs. 2 and 5.

Suitable means are provided for holding the shoe in either one of its two adjacent 105 positions, this being accomplished in the present embodiment of my invention by making the shoe curved, as shown in Fig. 3,

so that there will be sufficient frictional contact between the shoe and the tubular portion of the rib to hold the shoe in either adjusted position. Under ordinary circumstances, the shoe of each rib is in the position shown in Fig. 3, and when the parts are so arranged, the umbrella may be opened and closed as an ordinary umbrella. When the umbrella is thus opened, the strain on the braces 7 tends merely to force the shoes farther toward the joints of the ribs and to hold said shoes in this position. In order to fold the umbrella for packing, the umbrella is first closed, and when in this position, the shoes may all be slipped upwardly on the ribs by grasping the umbrella below the tip 3 with one hand and pushing upwardly on the runner with the other hand, this movement sliding all the shoes upwardly on the ribs so as to clear them from the joints 9. After this is accomplished, the sliding of the runner upwardly on the stem opens the umbrella out, as shown in full lines Fig. 2, the hinged ends 10 of the ribs 25 simply hanging vertically, and the continued upward movement of the runner carries the main portion 5 of the ribs backwardly against the tip 3, as shown in dotted lines Fig. 2. When in this position, the ends 10 are folded inwardly completely 30 against the main portion of the ribs, and the whole umbrella top is folded against the tip 3.

The handle 4 is provided with a joint at 35 so that the main portion of the handle can be removed from the tip 3. This joint is so placed that when the umbrella is folded, as shown in dotted lines Fig. 2, the runner 6 is carried above the joint so that 40 the handle may be disconnected from the tip. The frame of the umbrella thus occupies a minimum amount of space.

Preferably the handle 4 will be provided with one or more other joints, as 21, so that 45 it may be taken apart in sections, each of which is no longer than the folded umbrella frame. The entire umbrella may thus be condensed into a very compact bundle which can be readily put into a grip or suit case. 50 It will be noted that in my umbrella the ribs are jointed to fold inwardly, and that they are locked in their straightened position by means of shoes to which the braces are pivoted, and that one set of braces only 55 is used. The drawing shows and the specification describes one embodiment only of the invention.

25 designates a cap or protecting cover at the joint 9 of each rib to protect the cloth cover of the umbrella from being injured by 60 the folding of the rib.

Having fully described my invention, what I claim as new and desire to secure by Letters Patent is:—

1. In an umbrella, a handle or stem, ribs 65 hinged thereto, each rib having an inwardly-folding joint between its ends, a shoe slidable on each rib and adapted in one position to lock the joint, a brace pivoted to each shoe, and means to arrest the movement of each 70 shoe on its rib when the joint is unlocked.

2. In an umbrella, a handle, ribs hinged thereto and adapted to fold backwardly against the tip of the handle, each rib having a knuckle-joint intermediate of its ends and 75 adapted to fold inwardly, a runner on the handle, braces pivoted to the runner, and shoes slidably mounted on the ribs and connected to the braces, said shoes in one position adapted to span the joints on the ribs 80 and hold said ribs stiff.

3. In an umbrella, a handle, ribs pivoted thereto to fold backwardly against the tip thereof, said ribs being substantially U-shaped in cross section and each having an 85 inside joint intermediate of its ends, whereby the outer end of each rib may be folded inwardly against the inner side of the upper part thereof, a shoe within each rib, and braces connected to the shoes, each shoe being 90 adapted in one position to span the joint on the corresponding rib and hold said rib stiff in its straightened position.

4. In an umbrella, U-shaped ribs each 95 jointed intermediate of its ends, each rib having tubular portions adjacent the joint, a longitudinally-curved shoe slidable within each rib and adapted to penetrate the tubular portions and span the joint thereof, and braces pivoted to the shoes. 100

5. In an umbrella, the combination with a handle or stem of ribs hinged thereto, each rib having an inwardly-folding joint between its ends, a shoe on each rib, each shoe having a limited sliding movement sufficient only to lock and unlock the rib, and a brace pivoted to each shoe. 105

In testimony whereof, I have signed my name to this specification, in the presence of two subscribing witnesses.

HERBERT H. BROWN.
